Inventor,
Eugene Berruntz.
By Paul Baskerville Attest.

UNITED STATES PATENT OFFICE.

EUGENE DERUNTZ, OF ST. LOUIS, MISSOURI.

OIL-BURNING APPARATUS.

1,034,889.

Specification of Letters Patent.

Patented Aug. 6, 1912.

Application filed March 13, 1911. Serial No. 614,158.

To all whom it may concern:

Be it known that I, EUGENE DERUNTZ, a citizen of the United States, residing at St. Louis, Missouri, have invented a certain new and useful Improvement in Oil-Burning Apparatus, of which the following is a full, clear, and exact description, such as will enable others skilled in the art to which it appertains to make and use the same.

10 This invention relates to apparatuses for burning oil.

The main object of the invention is to provide an efficient oil-burning apparatus which is so designed that the oil will flow 15 freely to a steam nozzle from which a jet of perfectly dry steam escapes, which jet of steam atomizes the oil and converts it into a gas that is supplied to the combustion chamber.

20 Another object of my invention is to provide an oil-burning apparatus in which both the water heater and the member in which the steam is generated and raised to a high degree of temperature are exposed to the 25 fire in the combustion chamber. And still another object is to provide an oil-burning apparatus which is so designed that only a small quantity of hot water is supplied to a steam-generating member, thereby enabling 30 the apparatus to be started quickly and also causing the steam to be heated quickly to a very high degree.

The figure of the drawing is a vertical 35 sectional view of an oil-burning apparatus constructed in accordance with my invention.

Referring to the drawings which illustrate the preferred form of my invention, A designates a suitable source of water supply such, for example, as a tank provided 40 with an inlet pipe 1 and a float valve 2 for maintaining a constant level in the tank.

A supply tank A communicates with a water boiler, consisting of a drum 4 and a 45 tubular-shaped member 6, which are arranged in the combustion chamber B of the apparatus, and a steam super-heating member, which preferably consists of a large pipe 9, (which may be in the form of a coil), which is also arranged in the combustion chamber, so that both of said elements, namely, the water boiler and the steam super-heating members, are exposed directly 50 to the fire in the combustion chamber. Said water boiler may be formed in various ways, but I prefer to construct it in the

manner herein shown, a supply pipe 3 leading from the tank A to the drum 4, and the latter being provided at its top with a steam outlet pipe 5, leading to the tubular shaped member 6, from which a pipe 7 leads back to a riser 8, connected to the upper end of the water supply tank A. The steam super-heating member may also be constructed in various ways, but I prefer the construction 65 herein shown, on account of its simplicity and efficiency, the pipe or coil 9 being arranged in the combustion chamber and provided at one end with an outlet pipe 10 that leads to a steam nozzle 11. An inlet pipe 70 12 which communicates with the opposite end of the steam-superheating member 9, is arranged inside of the tubular-shaped member 6, and a needle valve 13 or other suitable device is provided for permitting a small 75 quantity of steam to enter the coil 9. In view of the fact that the member 9 is comparatively-large and is supplied with a very small quantity of steam, the latter will be quickly heated after it enters said member, 80 and in passing through said member it will be raised to a high degree of temperature so that it will be dry when it emerges from the upper end of said member.

The oil is contained in a reservoir or tank 85 14 from which a supply pipe 15 leads to a filtering device consisting of a cylindrical-shaped casing 16 having a tubular-shaped screen 17 arranged therein and provided adjacent its upper end with a layer of filtering material 18, the supply pipe 15 having a vertically disposed branch 15^a that projects downwardly through the top of the casing 16 and through the layer of filtering material 18 into the tubular-shaped screen 90 17. An outlet pipe 19 leads from the upper end of the casing 16 of the filtering device to a vertically disposed pipe 20 whose lower end terminates adjacent the steam nozzle 11 so as to cause the oil to drop downwardly 100 in front of said steam nozzle and thus be atomized and converted into gas by the jet of steam which constantly emerges from said steam nozzle. I prefer to provide the filtering device with a removable bottom 105 wall 21 so as to enable the sediment which collects in said device to be removed, and I also prefer to provide the oil-supply pipe 15 and the outlet pipe 19 from the filtering device with valves 15^b and 19^a, respectively, 110 for controlling the supply of oil to the steam nozzle 11 which is also provided with

a controlling valve 11^a. To insure a steady and free flow of oil from the oil-supply tank 14 I have provided the apparatus with means for heating the oil in the tank 14, the 5 means herein shown consisting of an extension 8^a from the riser 8, through which steam passes upwardly through the tank 14 and flows back through a return pipe 22 to the water tank A, said return pipe being 10 preferably provided with a gage 23, and the riser 8 with a safety valve 24. The operation of the apparatus is as follows: A small quantity of oil is poured 15 into the pan 25 that is arranged in the combustion chamber under the boiler and within a few minutes steam is generated and flows into the member 9, where it is raised to a very high degree of temperature so that a jet of dry steam will emerge from the 20 nozzle. The valve 19^a is regulated so as to cause the oil to drop from the lower end of the pipe 20, and, when said drops of oil come in contact with the jet of highly heated dry steam that emerges from the nozzle 11, 25 the oil will be atomized and converted into a highly combustible gas which produces a very hot flame in the combustion chamber, the steam which circulates up through the riser 8^a causing the oil in the tank 14 to 30 become heated, and the filtering device that is arranged between said oil-supply tank and the oil-discharge pipe 20 causing all of the dirt and foreign matter to be separated from the oil before it is mixed with the 35 steam. In view of the fact that both the boiler 4 and the steam-superheating member 9 are exposed directly to the flame in the combustion chamber, the apparatus can

be started quickly and the steam which is supplied to the steam nozzle 11 will be perfectly dry. 40

I do not wish it to be understood that my invention is limited to an apparatus of the exact construction herein shown, nor to an apparatus that comprises means for filtering and heating the oil before it is mixed with the jet of steam. It is desirable, however, to first heat the oil and filter it in the manner herein shown as this insures a constant and steady supply of fuel to the steam 50 nozzle. 45

Having thus described my invention, what I claim as new and desire to secure by Letters Patent is:

In an oil-burning furnace, the combination 55 with the combustion chamber and a burner therein comprising steam and oil nozzles, of a drum connected to a source of water supply and arranged in said chamber directly opposite to said burner, a boiler 60 consisting of a tubular member located above and connected to said drum, a pipe running longitudinally through said member and opening into the latter at one end, a valve to control the opening at the end of 65 said pipe, and a superheater connected to the other end of said pipe and to said steam nozzle. 70

In testimony whereof I hereunto affix my signature in the presence of two witnesses, 70 this ninth day of March 1911.

EUGENE DERUNTZ.
